UNITED STATES PATENT OFFICE.

JAMES R. FLEMING, OF SCRANTON, PENNSYLVANIA.

HINGED BOX WITH SEAT.

Application filed March 3, 1922. Serial No. 540,875.

To all whom it may concern:

Be it known that I, JAMES R. FLEMING, a citizen of the United States, and a resident of Scranton, in the county of Lackawanna and State of Pennsylvania, have invented in certain new and useful Improvements in Hinged Boxes with Seats, of which the following is a full, clear, and exact description.

This invention relates to journal boxes and in particular to a type especially adapted for use in conjunction with mine cars and trucks.

A particular object of the invention is the provision of a journal box which may be disposed exteriorly or interiorly of the car wheel.

Another object is to make provision in this type of journal box for varying gauges of track, whereby the same size of car body may be used regardless of the width of tracks.

All of these objects are provided for in the claims which follow.

Drawings.

Figure 1 is a side view of the journal box, showing the seat and the hinged door.

Figure 2 is a side view of the journal box, showing the seat and the hinged door.

Figure 3 is a side view of the journal box, showing the seat and the hinged door.

Figure 4 is a side view of the journal box, showing the seat and the hinged door.

Figure 5 is a side view of the journal box, showing the seat and the hinged door.

Figure 6 is a side view of the journal box, showing the seat and the hinged door.

of compensating for various widths of tracks.

Figure 7 is a perspective view of a portion of the journal box, the inside being shown to illustrate the pillars and waste retaining projections.

Figure 8 is a perspective view of the chair member which holds the bearing seat and which fits within the journal box.

Figure 9 is a perspective view of the top plate of the journal box, the underside thereof being exposed to show the bolt retaining lugs which form hinges for the housing member.

Description.

Referring more particularly to the drawings, 10 denotes in general a journal box which is mounted on the axle 11 of a mine car or truck adjacent the wheel 12 and comprises a top plate 13, and housing, 14, hinge

trunnions, 15, and a bearing seat 16. The top plate is formed by a single sheet of metal, which is cut out with a slot 17, which is of a width to receive the bearing seat 16, and which is provided with a slot 18, through which a hinge bolt 19 is passed, so as to hold the top plate 13 to the housing 14.

The top plate 13 is fastened to the housing 14 by a bolt 20, which passes through the top plate 13, the housing 14, and the bearing seat 16.

The bearing seat 16 is supported by the top plate 13, and is held in position by a bolt 21.

The top plate 13 is provided with a slot 17, through which the bearing seat 16 is held in position.

The bearing seat 16 is provided with a slot 18, through which a hinge bolt 19 is passed, so as to hold the bearing seat 16 to the top plate 13.

The bearing seat 16 is provided with a slot 19, through which a hinge bolt 20 is passed, so as to hold the bearing seat 16 to the top plate 13.

The bearing seat 16 is provided with a slot 20, through which a hinge bolt 21 is passed, so as to hold the bearing seat 16 to the top plate 13.

The bearing seat 16 is provided with a slot 21, through which a hinge bolt 22 is passed, so as to hold the bearing seat 16 to the top plate 13.

The bearing seat 16 is provided with a slot 22, through which a hinge bolt 23 is passed, so as to hold the bearing seat 16 to the top plate 13.

The bearing seat 16 is provided with a slot 23, through which a hinge bolt 24 is passed, so as to hold the bearing seat 16 to the top plate 13.

The bearing seat 16 is provided with a slot 24, through which a hinge bolt 25 is passed, so as to hold the bearing seat 16 to the top plate 13.

The bearing seat 16 is provided with a slot 25, through which a hinge bolt 26 is passed, so as to hold the bearing seat 16 to the top plate 13.

The bearing seat 16 is provided with a slot 26, through which a hinge bolt 27 is passed, so as to hold the bearing seat 16 to the top plate 13.

The bearing seat 16 is provided with a slot 27, through which a hinge bolt 28 is passed, so as to hold the bearing seat 16 to the top plate 13.

housing in the opposite side walls 30 thereof are the pillars 31 which support the chair 23 and prevent the lubricant holding waste from working up and jamming between the 5 said chair and walls of the housing.

A projecting boss 32 formed on the housing constitutes a latch for retaining said housing in closed position relatively to the plate 13 as it overlies a bolt 17.

- 10 The projecting points 33 formed in the bottom of the housing engage the lubricant holding waste or absorbent and prevent its collecting in one end of the housing thus unevenly distributing the oil and causing 15 unnecessary wear to the parts. In order to provide for oiling, the thrust plate 22 is drilled as at 34, the bore thus formed when matched with a similar one in the portion 20 of the plate 13, comprises a duct through 20 which oil may be poured into an open sump 35 formed in the top of the chair 23 and seat 27 and which is connected by the troughs 36 to a similar sump 38, adjacent the opposite end of said chair.
- 25 When a track of wider gauge than ordinary is used the wheels may be mounted outside of the journal boxes and in order that the axles may pass completely through said boxes, the normally closed end of the housing is left open as at 39.

When the track is of narrower gauge than ordinary the thrust plate 22 of the chair 23 is made thicker as at 40 to com-

pensate for the difference in track width. In this case the malleable seat 27 is also 35 extended to conform with the increased length of the chair as a whole.

Thus is can be seen that the location of the journal boxes will compensate for any width of track, as the wheels will be moved relatively thereto and no change in the car or truck body structure is necessary. Also, the complete and effectual lubrication necessary is maintained, as the absorbent material used such as cotton waste will always be 45 held in proper position about the axles.

Claim.

The combination with a vehicle having an axle and a wheel thereon, of a journal box comprising a housing open at its top and one end, a cover plate for said housing, a flange depending from said cover plate at the open end of the housing and recessed to provide a seat, the open end of said housing having its lower portion shaped to fit about the under portion of the axle and provide supporting shoulders at the sides of the axle, chair supports in said housing at opposite sides thereof, a chair block slid into said housing through the open end thereof and resting upon said shoulders and supports, and a wheel engaging collar on the outer end of said chair block fitting into the seat of said cover plate flange.

JAMES R. FLEMING.
